UNITED STATES PATENT OFFICE.

MICHAEL HERRON, OF BORDENTOWN, NEW JERSEY, ASSIGNOR OF ONE-HALF
TO JOHN HERRON AND JAMES HERRON, OF SAME PLACE.

CHUTE FOR DREDGING-MACHINES.

SPECIFICATION forming part of Letters Patent No. 397,985, dated February 19, 1889.

Application filed July 2, 1888. Serial No. 278,829. (No model.)

To all whom it may concern:

Be it known that I, MICHAEL HERRON, a citizen of the United States, residing at Bordentown, in the county of Burlington, State 5 of New Jersey, have invented a new and useful Improvement in Delivery-Chutes for Dredging-Machines, which improvement is fully set forth in the following specification and accompanying drawing.

10 My invention relates to improvements in dredging-machines, and has especial reference to a "delivery" or "discharge" chute for machines of this character.

The delivery-chutes at present in general 15 use are defective in that the sand or other material is only delivered to one portion of the receiving boat or vessel, and the vessel must be moved or the material distributed by manual labor. This defect, as is evident, involves a great expense and loss of time.

15 The leading object of my invention is the production of what may be termed an "adjustable delivery-chute," whereby the said chute may be adjusted to deliver or deposit 25 the material to any desired portion of the receiving-boat.

A further object is the production of a delivery-chute which will be of strong and durable construction in order to withstand the 30 hard usage, which can be operated with ease, and which can be applied to dredging-machines at a comparatively low figure.

To attain the objects mentioned, the invention consists in a delivery-chute capable of 35 vertical adjustment to incline the same to any desired angle; further, in a delivery-chute having hinged or jointed sections, whereby the chute may be lengthened or the sections adjusted to deliver the material to different 40 places; further, a delivery-chute consisting of hinged sections, one of said sections being provided with an inwardly-extending tail or guide, said sections being adjustable.

The figure represents a side elevation of a 45 delivery-chute embodying my invention, the buckets or carrier being shown in dotted lines.

Referring to the drawing, A designates the frame of the machine, having the standards or uprights a and a' and an inclined beam, a^2 . 50 B designates the chute proper, which at its inner end is journaled in the standards a' ,

and is adapted to be raised and lowered by means of the chains or ropes b , which are connected to the outer ends of the chute and pass over pulleys or sheaves b' and blocks b^2 55 on the standards a . From this construction it is evident that the chute may be raised and lowered or adjusted to any desired angle.

C designates a section having pivotally-depending arms projecting from the chute B, and 60 provided with a tail, C', by means of which the material can be delivered against the sides of the boat or at other points, as desired.

D designates a section hinged or jointed to arms projecting from the section C, as shown, 65 and chains d connect these arms with the chains b of section B, whereby the entire chute may be raised or lowered, if desired.

To the outer portion of the section D are attached chains d' , which pass over pulleys or 70 sheaves d^2 , arranged at proper points of the frame, and are operated, preferably, by means of a windlass, E, so as to adjust the section D.

From the foregoing it will be seen that I provide a chute by means of which material 75 may be received from the buckets or carrier and discharged at the end of the chute proper or at the outer ends of either of the sections C D, or at the tail C', it being seen that the sections may be placed in the positions shown 80 in full and dotted lines in the drawing.

Having thus described my invention, what I claim as new, and desire to secure by Letters Patent, is—

1. In a delivery-chute, the combination, with 85 the vertically-adjustable main section, of a section hinged thereto having an inwardly-extending tail or guide, substantially as described.

2. In a delivery-chute, the combination of a 90 main section, a section hinged thereto having a tail or guide, and a section hinged to said section, all of said sections being adjustable with relation to each other, substantially in the manner and for the purpose described. 95

3. In a dredging-machine, a sectional chute having its main part pivoted at or near one end, a section pivotally connected to the main part and having a tail portion, C', mechanism for raising and lowering the main portion, and 100 a chain connected to the section and to the said raising and lowering mechanism, said

parts being combined substantially as and for the purpose set forth.

4. In a dredging-machine, a sectional chute having a main portion pivotally secured to standards, a section with a tail portion pivotally connected to the main portion, and an end section pivotally secured to the section having the tail portion, and independent mechanisms for raising and lowering said main portion and sections, said parts being combined substantially as described.

5. A delivery-chute composed of hinged sections, one of said sections being provided with a tail below the main body of the chute, substantially as and for the purpose described.

6. A delivery-chute for a dredging-machine, consisting of a main portion and sections, the main portion and adjacent section having projecting arms, to which projecting arm of the main section the adjacent section and its 20 arms are pivotally attached, and mechanism for raising and lowering said sections, said parts combined substantially as described.

MICHAEL HERRON.
